DESIGN FOR A COIN REGISTER BANK

Jacob Farber, New York, N. Y.

Application April 11, 1935, Serial No. 56,326

Term of patent 3½ years

To all whom it may concern:

Be it known that I, Jacob Farber, a citizen of the United States and a resident of New York, in the county of Bronx, in the State of New York, have invented a new, original, and ornamental Design for a Coin Register Bank, of which the following is a specification, reference being had to the accompanying drawing, forming a part thereof.

The figure is a perspective view of a coin register bank, showing my design.

I claim:

The ornamental design for a coin register bank, as shown.

JACOB FARBER.
